UNITED STATES PATENT OFFICE.

WILLIS H. PROCTOR, OF CORNING, NEW YORK.

DEVICE FOR WARMING BEDS.

No. 882,714.

Specification of Letters Patent. Patented March 24, 1908.

Application filed May 11, 1907. Serial No. 373,124.

To all whom it may concern:

Be it known that I, WILLIS H. PROCTOR, a citizen of the United States, residing at Corning, in the county of Steuben and State of New York, have invented certain new and useful Improvements in Devices for Warming Beds; and I do hereby declare the following to be a full, clear, and exact description of the invention, such as will enable others skilled in the art to which it appertains to make and use the same.

This invention relates to improvements in devices for warming beds, and particularly to heating devices secured beneath the bed, and means for maintaining the heat in proximity to the bed.

The invention comprises the production of a housing adapted to fit upon or beneath a bedstead or be formed integral therewith and upon which mattress and bed clothing are to be placed.

The invention further comprises the production of a receptacle containing heating means for heating a housing placed beneath the mattress of the bed.

The invention also comprises the production of a housing located adjacent to a bedstead, heating means therefor and a hood for encircling the mattress and bed clothing of the bed.

The invention still further comprises the production of heating means, and means for regulating the amount of heat used and the distribution of the same.

The object in view is the production of a housing adapted for a bedstead, means located in the housing for heating the same, means for regulating the heat in said housing and for distributing the heat to the bed proper.

Another object in view is the production of means for warming beds, and a hood for partially encircling the mattress and bed clothing for retaining the heat adjacent thereto.

With these and other objects in view, the invention comprises certain novel constructions, combinations and arrangements of parts as will be hereinafter more fully described and claimed.

In the accompanying drawings:—Figure 1 is a side elevation of a bed embodying the features of the present invention, parts being broken away to better illustrate the interior mechanism thereof. Fig. 2 is a side elevation of my invention showing a slightly

modified form of heating means therefor. Fig. 3 is a side elevation of a bed formed according to the present invention showing a hood secured thereto. Fig. 4 is an end view 60 of Fig. 3. Fig. 5 is a section through Fig. 3 on line 5—5. Fig. 6 is a side elevation of a bed embodying a slightly modified form of my invention. Fig. 7 is a section through Fig. 6 on line 7—7. Fig. 8 is an enlarged, 65 detail, fragmentary view, partly in section, of one side of the frame of a bed showing the telescoping and securing means of the hood. Fig. 9 is a detail, fragmentary, sectional view showing the construction of the packing 70 forming part of the present invention. Fig. 10 is a perspective view of a heating box and register secured thereto forming a part of the present invention.

In constructing the present invention, I 75 preferably provide a housing 1 secured to end pieces 2 and 3. The housing 1 is designed to accommodate springs 4 of any usual or desired construction upon which is mounted a mattress 5 of any desired construction. Se- 80 cured to mattress 5, and also to end pieces 2 and 3 and housing 1 is a packing 6. As clearly seen in Fig. 9 packing 6 is made from a strip of any desired packing cloth 7 and is held in contact with end members 2 and 3 and housing 1 by a bar 8 and is connected to mattress 5 by stitching 9. It will be ob- 85 served that the packing 6 is of sufficient width to permit the mattress 5 to move up and down as may be desired without break- 90 ing the packing. The cloth or strip 7 of packing 6 is designed to be made from any flexible material, as cloth, that will prevent the passage of air therethrough so as to re- 95 tain all the heat in housing 1. Housing 1 is made of any desired height and of any de- 100 sired material but preferably from layers 10 of any heat non-conductor, and is designed to have positioned within the housing a box or second housing 11. The box or heat re- 105 taining housing 11 is designed to accommo- 110 date a heating means as radiator 12 which may be of any desired kind, but where electricity is convenient the same may be used by taking the current in through wire 13 to the electric radiator or heater 12. The current may be switched on and off by a suitable switch 14 at the head of the bed in convenient reach of any one using the bed. By this means the housing or box 11 may be heated to any desired degree and consequently housing 1 also may be provided with heat from said

box. Housing 11 is preferably made from some heat insulating material so that when lid 15 thereof is closed and door 16 is also closed, heat generated therein will not escape readily. Slide 15 is designed to be reciprocated by cords 17 and 18 for opening and closing the top of box 11. Door 16 is preferably opened by having a cord 19 secured to the same and to the outer end of slide 15 so that when slide 15 is opened door 16 will also be opened to the same relative extent, and when slide 15 is closed, door 16 also will close by gravity and will also be assisted in closing by a spring 20. The provision of door 16 as will be evident will permit the lower strata of air in housing 1 to enter the heated chamber or housing 11 and force outward the heated air into the upper part of housing 1 and against mattress 5. The degree to which door 16 and slide 15 are opened will regulate the amount of circulation of air through housing or box 11. In order to expose the interior of housing 1 or to remove heater 12, or for any other purpose, a door 21 is provided. I preferably construct door 21 at one end of housing 11 in order that when door 21 is opened housing 11 is free for inspection, but if desired housing 11 may be made with an independent opening.

In Fig. 2 will be seen a slightly modified form of heating means as radiator 22. Radiator 22 is of any desired construction for using either steam or hot water, and is supplied from any suitable source through pipes 23.

In Fig. 3 is disclosed a housing formed according to the preferred construction with any desired heating means positioned therein provided with a hood 24 for retaining heat adjacent the mattress 5. The hood 24 is preferably formed with arches 25 of any convenient number which are adapted to sustain the covering 26 composed preferably of cloth, as 27—27, for securing therebetween a filling 28, preferably of corrugated paper. The arch shaped members 25 have secured thereto projections 29 which are adapted to slide in ways 30, formed in the sides of housing 1. The top rail of the housing 1 is preferably made in two parts 31 and 32 as clearly seen in Fig. 5 for more easily forming slide ways 30. The covering 26 is preferably secured to arches 25 by securing means as tacks 33, and has its lower edge held in position by clamping rails as 34 which are secured near the ends 55 of the housing 1 by any suitable means as clamps 35.

It will be perfectly evident that if desirable tacks 33 may be omitted and the covering 26 may be loosely laid upon the arch shaped members 25 and held in place by means of the clamp rails 34 which pinches the lower edge of the same against the sides of the housing 1. The front end of hood 24 is to be closed by a curtain suspended from the head arch to fall to and be tucked about

the sleeper's neck to render this point air tight. The rear is closed by a suitable covering 36 of any desired material, but preferably of the same material as covering 26. As will be clearly seen in Fig. 4 the end covering 36 is secured in position by suitable means as tacks 37 and 38 to the end arch 25 and to the end piece 3 respectively. This will effectually prevent any heat escaping from the rear. The hood 26 is adapted to be reciprocated so that when in use the same is drawn forward until it covers or nearly covers the occupant's body, and then cords 17 and 18, or other means, are operated for permitting heat which escapes from the receptacle 11 to rise and fill the housing 1 and escape into the hood through means hereinafter fully described. In case the heat becomes too great the box or housing 11 may be closed or the heat turned off from the heating means as may be desired. When not in use the hood is forced toward the end member 3 and the member 29 permitting the arches 25 to be easily moved in that direction, yet hold the same in a relative correct position.

In order to provide means that may be easily regulated for the transmission of heated air from housing 1 to the interior of hood 26, I provide a plurality of pipes or members 39—39 and 40—40. The pipes 39—39 and 40—40 are designed to be positioned at end 3 of the housing and preferably secured thereto. Members or pipes 39—39 preferably extend between the end of mattress 5 and the end member 3 and reaches to only a short distance above mattress 5, but extends to almost the bottom of housing 1, while members 40—40 extend from near the top of the interior of housing 1 to near the top of the interior of hood 24. Members or pipes 40—40 are placed between mattress 5 and end piece 3 through packing 6 in a similar way to members 39—39. The members or pipes 39—39 are preferably open at both ends while members 40—40 are open at their lower end and provided at their upper end with covers or doors 41 which are designed to be opened by cords 42—42, which in turn are secured to a cord 43 and is designed to extend the full length of the hood 24 when the same is extended and have its end within easy reach of the occupant of the bed, so that when the hood is extended to its full length the cord 43 will be pulled and doors or covers 41—41 opened for permitting a free circulation of air from housing 1 to hood 24. The cords 43 are designed to pass over pulley 44 and to the front of the hood 24 and may be loosely secured in position or firmly secured to the arch nearest to end piece 2. If the end of cord 43 is firmly secured to the forward arch 25 and the hood 24 is extended to its full length the cord 43 will be pulled for opening covers 41—41 and the

covers will be held in an open position as long as the forward arch is held in its forward position.

In the modifications shown in Figs. 6, 7 and 8, I provide a bedstead having the usual end pieces 2' and 3' and side rails 2" and 3". Upon the rails 2" and 3" is mounted a housing 1' formed with rails 45 and 46 preferably formed in two parts, the inner part being termed supporting rails as 47 and 48. The supporting rails 47 and 48 are beveled as at 49 and 50 and are formed with apertures 51 and 52 for permitting air to circulate therethrough. Between the rails 45 and 46 are springs of the usual construction upon which is placed a mattress of any desired structure. The rails 45 and 46 are of sufficient distance apart to accommodate the mattress without permitting the same to cover the apertures 51 and 52. Within the housing 1' is located a box or receptacle 53, preferably lined with fire resisting material, as 54, and is provided with a lid 55. The lid 55 has secured thereto fire resisting material, as 56, and is adapted to slide in guide ways 57 and 58. Connected to one end of the slide 55 is a cord or rope 59 which extends to the end of the bed and passes over the pulley 60 and from thence up over the head of the bed for being conveniently reached by the occupant. When it is desired to move the lid 55 from off the receptacle 53 it is only necessary to pull upon the end of the rope or cord 59. A spring 61 is secured at one end to the lid 55 and at the other end to the receptacle 53 so that when the end of the cord 59 which passes over the end of the bed is released the lid 55 will be retracted to its normal position over the receptacle 59. At one end of the receptacle 59 is positioned a door 62 which is connected to the end of the lid 55 by any suitable means as cord 63 so that when the slide or lid 55 is opened, door 62 will also be opened to a corresponding degree for permitting air to circulate through box or housing 53. By the provision of the door 52 the cool air at the bottom of housing 51 is permitted to enter the heating box 53 and after being heated pass upward to the top of the box or housing 50 when the lid 55 is opened. Any heating means may be used in box 53 as for instance heated stones, electric radiators, as seen in Fig. 1, or a hot water or steam radiator as seen in Fig. 2.

55 Formed in the end of the end member 3' is a door 64 which is placed opposite the receptacle 53. This is adapted to permit ready access to box 53 and to the interior of the housing 1' generally.

60 By the structure shown in Figs. 6, 7 and 8 heat from the receptacle 55 will fill the box 1' and rise upward and pass through apertures 51 and 52 into a hood 65 constructed similarly to hood 24 in the preferred construction. From this it will be seen that the

occupant will be surrounded above and below by heated air.

If desirable a mattress may be provided of such width as to pass over apertures 51 and 52, and a packing interposed between the mattress and rails 47 and 48 for preventing any escape of heat therebetween, for instance, a strip of packing material of any desired kind may be secured to the edge of the mattress and passed around beneath the same for thoroughly preventing any heat passing upward.

When using packing as seen in Fig. 9, I preferably provide a groove in the side rails of the housing 1 and force bar 8 into the same after having previously placed the packing around the bar. The bar is then firmly secured in place by driving in tightly, or by any desired means, as clamps or screws as may be desired. The packing means are preferably designed to pass entirely around the housing so as to positively prevent any escape of air therefrom.

In the drawing I have shown a slide to regulate the heat discharged from the heating box, but it will be evident that a rotary register 64 of any ordinary or preferred construction might be substituted for the slide. It will also be evident that when an electric heater is used, the heating box may be dispensed with or used as preferred, the amount of heat being regulated by a suitable rheostat positioned at the head of the bed.

In some instances I find it advisable to provide a thermometer, as 65, of any desired type, that may be provided with an arm extending from the interior carrying the pointer for indicating the degrees of heat within the housing. If preferable the thermometer may be positioned in the housing and arranged to be seen through the glass panel or in any desired way that circumstances might require, the use of some thermometer being simply to provide means whereby the person using the device may regulate the heat to any desired extent.

What I claim is:—

1. In a device of the character described, the combination of a bed, a housing located under the bed, a heat retaining box positioned within the housing, heating means within the said box, a slidably mounted cover for the box, and means for sliding the cover to regulate the escape of the heat from the heat retaining box into the housing.
2. In a device of the character described, the combination of a bed, a housing located under the bed, a heat retaining box located within the housing, heating means within the said box, a cover slidably mounted upon the box, a spring normally holding the cover in a closed position, and means for sliding the cover to regulate the escape of heat from the heat retaining box into the housing.
3. In a device of the character described,

the combination of a bed, a housing located adjacent the bed, a heat retaining box within the housing, heating means within the box, and a bodily removable cover for regulating 5 the escape of the heat from the heat retaining box into the housing.

4. In a bed, the combination with a bed-
stead, of a housing mounted thereon, rails
secured to the top of said housing, a mat-
tress mounted so as to impinge against said
rails, said rails being formed with apertures
therein, and heat containing means posi-
tioned within said housing.

5. In a bed, the combination with a bed-
stead, of a housing mounted thereon, heating
means positioned within said housing, a mat-
tress mounted above said housing, rails for
supporting said mattress provided with aper-
tures for permitting heat to escape from said
housing, and a hood positioned above said
mattress for retaining said heat, said hood
being movable so as to inclose any desired
portion of the mattress.

6. In a bed, the combination with a bed-
stead, of a housing therefor, heating means
positioned within said housing, rails secured
to said housing and formed with apertures
therein for permitting heat to escape there-
through, a mattress impinging against said
rails, a hood surrounding said mattress, and
clamping means for holding said hood in
operative position.

7. In a device of the character described,
the combination of a body, a housing posi-
tioned under the bed, heating means located
within the housing, rails at the upper portion
of the housing, and fitting against the sides
of the bed, the said rails being provided with
perforations, and a hood mounted upon the
rails, and adapted to confine the heat escap-
ing through the perforations therein.

8. In a device of the character described,
the combination of a housing, heating means
located within the housing, rails secured to
the housing and having guideways formed
therein, a mattress mounted upon the hous-
ing, and a hood adjustably mounted over the
mattress and adapted to be moved back and
forth within the before-mentioned guideways
50 in the rails

9. In a device of the character described,
the combination of a bed, a housing therefor,
a heat retaining box positioned within the
housing, heating means within said box, a re-
55 movable canopy for said bed; and means for
regulating the position of the canopy.

10. A device of the character described,

comprising a bed, a housing therefor, a
heater positioned in said housing, a second
housing for said heater, said second housing 60
being formed with a slide and a door, said
slide and said door being adapted to be
opened and closed at the same time, and
means for opening and closing said door and
said slide.

65 11. A device of the character described,
comprising a bed provided with a mattress, a
housing therefor provided with a rail at its
upper edge, packing interposed between said
rail and said mattress, and means for secur- 70
ing said packing to said rail and means for
securing said packing to said mattress.

75 12. A device of the character described,
comprising a bed provided with a mattress, a
housing provided with a rail at its upper edge
for said bed, heating means positioned in said
housing, a packing for preventing circulation
of air between said rail and said mattress, a
binding strip for holding one end of said
packing to said rail and means for securing 80
the other end to said mattress.

85 13. A device of the character described,
comprising a bed provided with a mattress, a
housing therefor, means for heating the air
in said housing, a hood secured over said
bed, tubes communicating with the interior
of said hood and the interior of said housing,
and means for regulating the flow of air
through said tubes.

90 14. A device of the character described,
comprising a bed, a housing positioned be-
neath said bed, a heating means for heating
the air in said housing, a hood for said bed,
communicating tubes for providing com-
munication between said hood and said hous-
ing and covers for some of said tubes for
95 regulating the circulation of air between said
housing and said hood.

100 15. A device of the character described,
comprising a bed, a housing therefor, means
for heating the air contained in said housing,
a hood for said bed, communicating passag-
eways for preventing circulation of air be-
tween said hood and said housing, means for
regulating the amount of air permitted to 105
pass through said passageways, and a cord
secured to said hood for operating said reg-
ulating means.

105 In testimony whereof I affix my signature
in presence of two witnesses.
